E. I. STAPLES

LIQUID FUEL BURNER

Filed April 23, 1923

Earle I. Staples,
INVENTOR.

BY *Victor J. Evans.*

ATTORNEY.

WITNESS:

J. B. White.

UNITED STATES PATENT OFFICE.

TABLE I. STAPLES, OF NEW YORK, N. Y.

LIQUID-FUEL BURNER.

Application filed April 23, 1923. Serial No. 634,191.

This invention relates to mechanical oil burners and has for its primary object the provision of a burner structure which is associated with a furnace front in a manner which will cause effective confinement of the heat within the furnace and hold the heat against undue escape to the fire box opening and from the stack.

A further object of the invention resides in 10 a construction of this character wherein all parts thereof are adjustable from outside of the furnace.

Another object of the invention is to provide a burner associated with novel means 15 whereby quick access may be had to the furnace.

A still further object of the invention is to provide means which will readily adapt the burner to furnaces of respectively different 20 types.

A still further object of the invention is to provide a mechanical burner having means adapted to be secured to a furnace front in line with the fire box opening and which will 25 include mechanism for readily effecting a forced draft and which said mechanism is adjustable from a point outside the furnace.

With these and other objects in view, the invention resides in certain novel construction 30 and combination and arrangement of parts, the essential features of which are hereinafter fully described, are particularly pointed out in the appended claim, and are illustrated in the accompanying drawing, in which:—

35 Figure 1 is a vertical section through a portion of a furnace showing my improved front means and the manner of associating a burner with said means, the arrangement being adapted to a Scotch boiler.

40 Figure 2 is a similar view showing a slightly modified application of the structure.

Figure 3 is a front view thereof, the furnace being omitted.

45 Figure 4 is a perspective view of the front furnace.

The invention is characterized by a burner structure 10 which includes a yoke 11 which accommodates a nipple 16 adapted to be connected in any suitable well-known manner 50 with a liquid fuel supply source, not shown. A fuel pipe (not shown) is in communication with the nipple and has a nozzle at its free end which is controlled by a stem having a hand wheel 36 at its outer end.

55 A guide and air feeding pipe or equivalent

means 39 is threadedly connected at one of its ends with the yoke 11 and freely surrounds the fuel pipe of the burner structure. This pipe 39 is approximately co-extensive with the fuel pipe and terminates at the tip of the 60 burner structure. It also passes through a hub 40 in a spider 41 of a supporting means as clearly shown in Figure 4 and it is observed that the spider 41 is secured within an open ended cylindrical extension 42 which 65 is hinged at 43 to a front flange 44 and adapted to be clamped with respect thereto by pivotally supported clamping bolts 45 carried by the flange 44 and co-acting with bifurcated lugs 46 on said extension 42. The 70 front flange 44 is provided with an asbestos packing ring 47 against which the inner end of the extension 42 bears. The front flange 44 is associated with a plate 48 secured at 49 to the brick arch 50 of the furnace structure 75 51 at one side of the fire box opening 52. Interposed between the plate 48 and the flange 44 is an asbestos packing 53. From this construction it is observed that the annular extension 42 may be effectively mounted on 80 furnaces of various well-known types. It will subsequently be observed that the extension 42 and its spider 41 constitute mounting for my damper mechanism to be referred to hereinafter.

85 As stated, the pipe 39 passes through the hub 40 of aforesaid spider 41, the medial portion of the pipe being preferably at the hub so that portions of the pipe of approximately equal length extend respectively to opposite 90 sides of the spider. This disposes the tip end of the burner inwardly of the extension 42 in line with the fire box opening 52. The purpose of this arrangement will also clearly appear hereinafter. Mounted to slide on the exposed or external portion of the pipe 39 is a circular damper 54 having a hub 55 carrying a set screw 56 engageable with the pipe to definitely or securely hold the damper in its position of adjustment with respect to 100 the outer open end of the extension 42. This damper is provided with a lining 57 of asbestos which is adapted to seat against the outer edge of the extension 42 when the damper is fully closed. The damper carries 105 handles 58 by means of which it can be moved conveniently by hand. Formed in the damper are peep holes 59 normally covered by swinging closures 60 which may be easily moved to open position in order that the operation of 110

the burner may be observed from outside the furnace.

Mounted to slide upon the inner portion of the pipe 39 is a concavo-convex damper 60'

5 having its concave side facing the fire box opening 52. The diameter of the fire box opening is greater than that of the damper 60'. As one illustration of desirable proportions of these parts, the diameter of the opening 52 should measure in practice in certain types of furnaces 18 inches and the diameter of the damper 60' approximately fifteen inches. This always defines a circular space

10 between the marginal edge of said damper 60' and the walls of the opening 52. This

15 damper 60' is provided with a hub 61 which may be secured to the pipe 39 by a set screw 62. The hub has a portion 63 bounded by the concave face of the damper 60' and

20 supported therefrom is a member 63^a of a substantially similar shape as that of the damper 60'. The purpose of this member 63^a is to guard the damper 60' against the action of excessive heat of the flame

25 so that it will not be prematurely destroyed or burnt out. The member 63^a is disposed in front of draft openings 64 arranged in a circular series around the damper 60' and disposed medially thereof, whereby

30 a direct line of suction is created between the center portion of the damper 60' and the outer open end of the extension 42. The openings 64 aside from causing the proper amount of draft to be supplied at the tip of

35 the burner serves to constantly cause cool outside air to move directly through the damper 60' to keep the same at a lower temperature than is otherwise possible. The hub of the damper 60' embraces the inner end of

40 pipe 39 and said end is disposed axially of the damper 60' and mating member 63^a. The damper 60' is provided with rods 65 which pass through the damper 54 so as to freely slide therein and the free end of these rods,

forwardly of said damper 54 are provided 45 with handles 66. This permits the damper 60' to be controlled from a point outside the furnace.

The arch 50 is in open communication with the lower portion of the shell 67 of the furnace and as illustrated the space 68 between the arch and the shell opens at 69 at a point under the damper 60'. This provides for a rear under draft and serves to protect the furnace keelson to permit air to be drawn off 55 but from under the arch of the furnace and into the fire box opening.

In the form shown in Figure 4, the furnace is of the natural draft Scotch marine type provided with a brick ring 70 which extends 60 around the fire box opening of the furnace. The remaining features of this form of the invention are the same as previously described herein.

What is claimed as new is:—

In an oil burning apparatus, an open ended member adapted to be secured to a furnace in a line with the fire box opening thereof, a concavo-convex damper movably mounted for adjustment with respect to one side of the 70 fire box opening, a second damper controlling the open ended member and adjustable with relation thereto to form a draft opening between the furnace and the second damper, a burner structure carrying both dampers and 75 having its burner end disposed within the concave face of the concavo-convex damper which is provided with a series of openings, and a substantially concavo-convex guard member having its convexed face mounted 80 against the concave face of said damper in a manner whereby said guard member is disposed in the path of air from the series of openings.

In testimony whereof I have affixed my 85 signature.

EARLE I. STAPLES.
